VOLTAGE MULTIPLYING CIRCUITS,
INCLUDING A SWITCH THEREFOR

Jess M. Reed, Inglewood, Calif.

Application July 21, 1947, Serial No. 762,253

5 Claims. (Cl. 171—97)

1

In undertaking to build up a voltage potential sufficiently great to operate stroboscope tubes, or for other uses requiring relatively high voltages, resort has been made to doubling the voltage of a primary energy source, that is, by the use of condensers and a battery, the voltage across the terminals of series connected condensers equals the voltage of the primary source times the number of condensers charged by the primary source, thus if a group of 31 condensers are individually charged in parallel with a primary voltage source (battery) of 90 volts, a potential of 2880 volts is obtainable by throwing the battery in series circuit with the discharging condensers.

Since a potential of approximately 2880 volts is required for efficient use of stroboscope tubes for photographic purposes, it will be apparent that the afore-stated method of arriving at such a voltage potential entails the use of an excessive weight and number of condensers insofar as portability is concerned, as well as the element of time required to charge each of the condensers in the pack comprising the unit. Also, the element of cost is a considerable item, which when taken together with the above mentioned considerations operates against popularity of use in on the spot photography.

In contra-distinction to the afore-described method of building up a voltage potential sufficiently great to operate photographic flash lighting equipment, I have conceived of a method of utilization of condensers, charged one at a time with a novel switching means, and discharged in series, wherein the potential acquired is not that of simple arithmetical progression, but on the contrary is of the order of geometrical progression, whereby I obtain a potential of 2880 volts on discharge of but 6 condensers in series with a primary source of 90 volts, thereby effecting a great saving in weight of the unit as a whole, a saving of time required to successively charge each of the condensers, and a very real saving in invested capital.

Accordingly it may be stated as being a primary object of the invention to provide a light weight, low cost, and quickly charged pack of condensers possessing a voltage potential sufficiently great to functionally operate photographic flash-lighting equipment, and/or for other relatively high voltage requirements.

A further object of the invention is to provide a circuit including a switch therefor, whereby a voltage potential may be built up to a total required voltage in increments arrived at in the order of geometrical progression.

A still further object of the invention is to provide a driven switch adapted in a single cycle of operation to be placed in circuit with a progressively increasing number of condensers, and

2

being so constructed as to apply to each of successive ones of said condensers, the accumulated potential of each and all of previously charged condensers, whereby upon charging each of a successive number of condensers, the potential of the last charged condenser is that of the last previously charged condenser, plus the potential of other previously charged condensers; plus the voltage of the primary source, carried through any increasing number of condenser charging operations.

In addition to the aforementioned objects of the invention, other objects thereof, as well as features and advantages, derivable therefrom, may be noted from the accompanying drawing, the detailed specification, and the subjoined claims.

In the drawing, of which there are 2 sheets:

Figure 1 is a development of the rotatable switch shown in Figure 8, the view shows the several segments of the switch, the related connections thereof for progressive charging of a plural number of condensers, and also shows a primary voltage source functionally connected with the switch.

Figures 2 to 7 inclusive show or rather illustrate the charging of a progressively increasing number of condensers, each figure of the group being identical to the preceding figure except that in each succeeding figure another condenser is added to those previously shown, and in effect is illustrative of the end result obtained through the circuit and switch shown in Figure 1.

Figure 8 is a front elevational view of the switch employed in developing the invention.

Figure 9 is a schematic view illustrative of the switch shown in Figure 8, the view shows the several contact rings of the switch as well as the electrical circuit involved therein, whereby it is possible to charge condensers to a potential within the precept of the second and third objects of the invention as aforementioned.

In the drawing the reference character 14 indicates the switch involved in the present invention, and which as shown in Figure 9 comprises a rotatable cylinder 16 formed of a dielectric material 18 supported upon bearings 20 in brackets 22, and which is preferably driven by a motor 22 or other power unit such as a spring suitably connected thereto.

At variable intervals along the length of the dielectric cylinder 16 I place metallic rings 24 of which in the present illustration there are 13 individual bands, certain of which are functionally operable in pairs, the spacing between bands of each pair thereof, and between pairs of bands, may be and is variable to provide ample spark gap clearance, and in practice would vary with the voltage across any pair of bands and/or between adjacent pairs of bands.

As shown in Figures 1, 8, and 9, excepting for the first two and the last band of the thirteen bands shown, each band connected in series across a condenser is formed with an air gap 26 which extends uniformly across the face of the cylinder 16 in a horizontal line whereby the ends of the several bands directly involved in series circuit with a condenser are separated from one another at a point beginning in common with one another and which gap 26 may be indicated in Figure 1 as being coincidental with the numeral 27.

Additionally each pair of bands is segmented, that is, band pair 28 is formed with the short segment 28a separated from the greater portion 32 by means of an air gap 34. Likewise band pair 31 is formed with a segment 31a, although as reference to the drawing will show, the segment 31a is of greater length than the segment 28a, and the segment 31a is separated from the greater portion 31b by an air gap 31c, and so in like manner the numerals 33, 35 and 37 indicate additional pairs of bands directly connected across one of the remaining condensers 44, 46 or 48, and each of the latter mentioned pairs of bands are also segmented, the segments 33a, 35a and 37a thereof increasing in length as you move progressively from band pair 33 to 35 to 37 across the face of the switch 14, that is, the segment 33a of the band pair 33 is of greater length than segment 31a, likewise the segment 35a of band pair 35 is of greater length than that of the preceding band pair, and thusly with respect to the whole thereof.

In the present illustration there are 5 condensers to be successively charged in series across the band pairs 28, 31, 33, 35, and 37, all to be charged in sequence of rotation of the switch 14, hence each pair of bands is formed with segments of increasing length as aforementioned, whereby successive ones of the condensers may be charged as the switch 14 is rotated, and additionally, to again impress a charge upon previously charged condensers which have laid a combined voltage across a last condenser in the condenser charging circuit, and in addition thereto, a 6th condenser, or condenser 86 is charged in series with the combined accumulated potential of each of the condensers 40 to 48, and additionally including the potential of the battery 60.

If a greater number of condensers were to be charged, then for a given size of switch, there would be a proportionately greater number of bands, although the segments thereof would be of shorter length to meet physical limitations thereof.

As shown in Figures 1 and 9, the band pair 56 constitute closed ribbons of metal extending around the periphery of the cylinder 18 and are energized by means of suitable sliding brush contacts 58a and 58b in circuit with an energy source or battery 60, the potential across the terminals of which will be considered as being 90 volts for the purpose of this specification.

Since for the purpose of this specification it is proposed to successively charge the five condensers 40 to 48 inclusive in series with the battery 60, although it will be recognized that a greater or lesser number of condensers may be charged, depending upon the ultimate voltage desired, it is necessary that there be 5 pairs or 10 individual bands, each of which is segmented as aforementioned, and in addition thereto, there is an additional continuous strip or closed band 62 which is brought into functional use following

charging of the last of the above mentioned condensers, thus in the present illustration we have a total of 13 individual bands, certain of which are segmented, while others thereof are not segmented.

Of the aforementioned bands, band 56a, and elements 28a', 31a', 33a', 35a', and 37a' of band segments 28a, 31a, 33a, 35a and 37a are connected in common by a lead 65 with the positive terminal 10 of the battery 60 through the brush contact 58a, while of the aforementioned bands, band 56b and band 28a'' of segment 28a are electrically connected by means of a lead 64, and the brush contact 58b with the negative terminal of the battery 60.

The band portion 28b of the band pair 28 is electrically connected through lead 66 with the band portion 31a'' of the band pair 31, also, the band portion 31b is electrically connected through lead 68 with the band portion 33a'' of band pair 33; also, band portion 33b is electrically connected through lead 70 with band portion 35a'' of band pair 35; also, band portion 35b is electrically connected through lead 72 to band portion 37a'' of the band pair 37.

It is also to be noted that of the 13 individual bands aforementioned, band 56b and band 28c are electrically connected through lead 28g; also, band 28b and 31c are electrically connected through lead 31g; also, band portion 31b and band 33c are electrically connected through lead 33g; also, band 33b and band portion 35c are electrically connected through lead 35g; also, band 35b and band portion 37c are electrically connected through lead 37g; also, band portion 37b and band 62 are electrically connected through lead 61'.

Sliding contact 49a upon the band 62 operating through the lead 82 and lead 84, places the bands and hence the condensers 40 to 48 in series connection with an energy storage condenser 86 at the termination of one complete rotation of the switch 14, as will be more fully set forth in the description of sequence of operation. Lead 88 connects the opposite side of the condenser 86 with the battery 60, and the leads 82—84 enable the last mentioned condensers to be thrown into series connection with the high voltage condenser 86 upon completion of one full rotation 50 of the switch 14 as aforementioned.

The preceding description is believed to be inclusive of physical structure involved in the present invention, wherefor, in the interest of complete clarity thereof, I will now describe functional operation thereof through one rotation of the switch 14.

With the several condensers and all other physical structure connected as afore-described, it is only necessary to close the switch 120 to energize and rotate the motor 122 and the direct coupled switch 14. Upon closing switch 61, band 56a and segment bands 28a', 31a', 33a', 35a', and 37a', being connected with the positive side of the battery 60, may be considered as being energized extensions of the battery 60. Also, since band 56b and band segment 28a'' are connected through lead 64, and further, since band portion 28c is electrically connected with band 56b through the lead 28g, these enumerated parts 65 may be considered as being energized extensions of the negative side of the battery 60, and thus the segment 28a being energized, places a charge of 90 volts across the condenser 40 through the medium of the brush contacts 40a and 40b (see 70 Figure 9).

To aid in following the circuit through positions 2 to 6 inclusive, the position of successively charged condensers is shown in dotted lines in each of the positions 2 to 5 inclusive. It is to be noted in this connection that presently charged condensers are shown as being across the band segment of the position concerned, while other condensers are shown as being across the remainder portion of the bands.

Position 2.—This position places condenser 42 across band segment 31a through brush contacts 42a and 42b (see dotted lines for schematic position of condenser 40). Energy flows from the positive side of the battery 60, through lead 65, segment 31a', across condenser 42, through band segment 31a'', through lead 66, band 28b, condenser 40, through band portion 28c, lead 28g, to band 56b, and thence to the negative side of the battery 60.

Closure of the above described series circuit places the 90 volt charge of condenser 40 across condenser 42, which additionally takes a 90 volt charge from the battery 60, whereby condenser 42 acquires a total charge of 180 volts. Condenser 40 retaining a charge of 90 volts by reason of being previously charged when on bands 28 and 28''.

Position 3.—This position places condenser 44 across band segment 33a through brush contacts 44a and 44b (see dotted lines for schematic position of condensers 44, 42, and 40). Energy flows from battery 60 through lead 65, segment band 33a', across condenser 44, through segment band 33a'', through lead 68, band 31b, across condenser 42, band 31c, lead 31g, through band 28b, across condenser 40, through band 28c, and lead 28g to band 56b and the negative side of the battery 60. This position now places the 180 volt potential of condenser 42, plus the 90 volt potential of condenser 40, plus the 90 volt potential of the battery 60 across condenser 44 which has now assumed the above total voltage, or a potential of 360 volts. Concurrently with establishing the new potential in condenser 44, condenser 42 retains a 180 volt charge, while condenser 40 retains a 90 volt charge.

Position 4.—This position places condenser 46 across band segment 35a through brush contacts 46a and 46b (see dotted lines for schematic position of condensers 40, 42, 44 and 46). Energy flows from the battery 60 through band 56a and lead 65 to band segment 35a', thence across the condenser 46 through band portion 35a'', thence through lead 70, band 33b, across condenser 44, through band 33c, lead 33g, band 31b, across condenser 42, through band 31c, lead 31g, band 28b, across condenser 40, through band 28c, lead 28g, to band 56b and battery 60.

Condenser 46 has now assumed the 360 volt charge of condenser 44, the 180 volt charge of condenser 42, the 90 volt charge of condenser 40, and the 90 volt potential of the battery 60, or a total voltage charge of 720 volts, while at the same time and in series connection, condenser 44 retains a charge of 360 volts, condenser 42 retains a charge of 180 volts, and condenser 40 retains a charge of 90 volts.

Position 5.—Upon rotation of the switch to position 5, the condenser 48 is across band segments 37a through brush contacts 48a and 48b (see dotted lines for schematic position of condensers 46, 44, 42, and 40). Energy now flows from the battery through band 56a, lead 65, segment band 37a', across condenser 48, through segment band 37a'', through lead 72, band 35b,

across condenser 46, through band 35c, lead 35g, band 33b, across condenser 44, through band 33c, lead 33g, band 31b, across condenser 42, through band 31c, lead 31g, band 28b, across condenser 40, to band 28c, lead 28g, to band 56b, and thence to the battery 60.

Condenser 48 has now assumed the potential of the condenser 46, or 720 volts; the potential of condenser 44 or 360 volts; the potential of condenser 42 or 180 volts; the potential of condenser 40 or 90 volts; and the potential of the battery 60, or 90 volts, for a total charge of 1440 volts. At the same time the condensers 40 to 46 retain their respective charges of 90 volts, 180 volts, 360 volts and 720 volts.

Position 6.—In this position the switch 14 has rotated sufficiently to place all of the brush contacts 40a and 40b, 42a and 42b, 44a and 44b, 46a and 46b, and 48a and 48b across the remainder portion of the respective segmented bands in a process which began with and is coincidental with position 1 (see dotted lines, Figure 1, position 6). In this position the condensers 40 to 48 are in series with one another, but are across the condenser 86 through lead 61', the continuous band 62, brush contact 49a, leads 82 and 84 on one hand, and oppositely through lead 88, brush contact 58a, and band 56a.

Since the combined potential of the condensers 40 to 48 and the battery 60 is thus placed across condenser 86, this unit assumes a charge of 2880 volts, and is in relatively short term equilibrium with the 1440 volt potential of condenser 48, the 720 volt potential of condenser 46, 360 volt potential of condenser 44, the 180 volt potential of condenser 42, the 90 volt potential of condenser 40, and the 90 volt potential of battery 60, and the equilibrium thus established, remains thus, pending ultimate dissipation thereof, or discharge through leads 130 and 132 to a circuit of use, which while not shown in the drawing, could be among other uses, a stroboscope for flash photographic purposes.

Functional operation of the switch 14 has been described through 6 positions to show that a potential of 2880 volts is obtainable through employment of this invention as compared with the use of 31 condensers in currently used methods of voltage manipulation for similar uses. The voltage of 2880 having been arbitrarily used for the reason that it is sufficiently high to functionally operate a stroboscope for photographic purposes. Lower or higher voltages are obtainable in a master condenser of an energy storage type by increasing or decreasing the number of intermediate condensers as represented by the condensers 40 to 48 inclusive, and of course creating a lesser or greater number of segmented band in the switch, as aforescribed.

From the preceding description it will be apparent that the voltage potential obtainable across the condenser 86 is far in excess of that obtainable through currently employed methods of voltage doubling, employing the same number, weight and capacity of condensers. Also, the voltage obtainable is quickly arrived at, and hence is of distinct advantage to news photographers, and others engaged in on the spot photography.

Having thus described my invention, that which I declare to be new and which I desire to protect by Letters Patent, is:

I claim:

1. In a voltage multiplying circuit, in combination, a rotatable drum type switch having con-

tact faces thereon, certain of said contact faces being continuous and others thereof being formed with separated segment and remainder portions, leads connecting certain ones of said continuous contact faces and segmented and remainder portions, and condensers, certain of said condensers being so placed with respect to said contact faces and leads as to be progressively brought across said contact faces during rotation of said switch, a primary battery, slide contacts connecting said battery and certain of said continuous contact faces, and switch means to control the flow of energy from said battery to said rotatable switch, said circuit being so organized as to enable a first condenser to be charged to the potential of said primary battery and other subsequent condensers to be charged to the additive potential of previously charged condensers plus the potential of said primary battery as said switch in rotation causes successive condensers to be placed across segments of said contact faces and remainder portions of said contact faces.

2. In a voltage multiplying circuit for photoflash units and like purposes, a plural number of condensers, a primary source of energy, an energy storage condenser, and switching means, said switching means being successively in circuit during a cycle of operation with all of said condensers and said primary energy source, said switching means being so constructed as to effect a voltage potential in said energy storage condenser arrived at in increments of a total potential, proportional to a geometric progression with respect to said primary energy source.

3. In a voltage multiplying circuit, in combination, a rotatable drum type switch having contact faces thereon, certain of said contact faces being continuous and others thereof being formed with a segmented portion and a separated remainder portion, leads connecting certain remainder portions of contact faces and one continuous contact face, another lead, said last mentioned lead connecting one of said continuous contact faces with certain individual contact faces of said segmented portions, a lead connecting a remainder portion of a contact face with a contact face of a segmented portion, a plural number of condensers, certain of said condensers being successively in additive series connection with a voltage source and with one another and across a remainder one thereof and in electrical circuit across said contact faces upon completion of a cycle of operation, a single condenser, said single condenser being electrically connected across all other mentioned condensers upon completion of a single rotation of said switch, and a primary battery connected to two of said continuous contact faces, said contact faces being so connected with respect to one another and so related to said condensers that progressive rotation of said switch through a cycle of operation lays a charge across successive ones of said condensers whereby the potential of a last charged condenser equals the added potential of all previously charged condensers plus the potential of said primary battery.

4. A voltage multiplying circuit, in combination, a rotatable drum type switch having annular contact faces thereon, a primary battery in circuit therewith, means to conduct electrical energy to successive one of said contact faces during rotation of said switch, means to electrically connect

certain of said contact faces with one another, others of said contact faces being unconnected with respect to one another, a plural number of condensers, said condensers being successively placed and retained in series connection with one another across said contact faces during one rotation of said switch, and a single condenser, said last mentioned condenser being across all of said condensers and said battery upon completion of one rotation of said switch, said contact faces and electrical connections being so related to one another in an electrical sense as to impress successive charges of electrical potential across a successively increasing number of condensers whereby during intermediate rotation of said switch the potential acquired by a last charged condenser is the accumulated additive potential of previously charged condensers, and whereby upon completion of one rotation of said switch said single condenser acquires the accumulated additive potential of each and all condensers in series connection with one another and including the potential of said battery.

5. In a voltage multiplying circuit, a rotatable switch having a dielectric cylindrical base therein, a plural number of bands on said base, certain of said bands being continuous and certain others of said bands being grouped in pairs having a segmented portion and a remainder portion separated with respect to one another, a primary battery in circuit with a pair of said continuous bands, means electrically connecting one band of said pair of continuous bands with one band of each of said segments, means connecting the other band of said pair of continuous bands with the other and complementary band of a single segment, and means connecting one portion of each paired remainder band portion with the unconnected portion of each of said band segments, certain of the remainder portions of said pairs of bands being directly connected with one another and with one of said continuous bands, and another continuous band, said last mentioned band being directly connected to a remainder portion of one band of a pair of bands, and condensers, certain of said condensers being successively in additive series connection with a voltage source and with one another and across a remainder one thereof and being first placed across segmented portions and then across remainder portions of said bands in sequence with rotation of said switch, and another condenser, said last mentioned condenser being in circuit across all of said condensers and said battery upon completion of a single rotation of said switch, whereby said single condenser accumulates additively the electrical potential possessed by all individual condensers and said primary battery in series connection with one another.
